(57) **CLAIM**

The ornamental design for a hutch, as shown and described.

DESCRIPTION

FIG. 1 is a perspective view of the hutch according to my claimed design; the back bottom support and shelves are not part of the claimed design and are shown in phantom;

FIG. 2 is a top plan view thereof;

FIG. 3 is a front elevation view thereof; and,

FIG. 4 is a right side elevation view thereof; the left side elevation view is a mirror image of the right side elevation view and is therefore not illustrated.

The back and underside of the hutch are not shown as they are not part of the claimed design.
